UNITED STATES PATENT OFFICE.

THOMAS E. MARTIN, OF BUFFALO, NEW YORK.

FURNACE GRATE.

Application filed March 29, 1920. Serial No. 369,602.

To all whom it may concern:

Be it known that I, THOMAS E. MARTIN, a citizen of the United States of America, and a resident of Buffalo, in the county of Erie and State of New York, have invented certain new and useful Improvements in Furnace Grates, of which the following is a specification.

This invention relates to improvements in furnace grates. One of the objects of my invention is to provide such construction of the grates as to provide the maximum openings for admission of air to the fuel and for the elimination of ashes and cinders produced by combustion of the said fuel, without waste of unburned or but partially burned fuel during the process of combustion, or when it becomes necessary to cause a movement of the grates to produce the elimination of such ashes and cinders as do not fall through the openings by the slight disturbance or movement of fuel caused by the natural process of combustion.

Another object is to provide a fuel supporting surface composed of a multiplicity of corrugated segments arranged side by side upon supporting cross bars, the openings between said segments produced by the corrugations thereon being relatively large or small, and readily changeable from large to small, or vice versa, as may be best adapted to the character of fuel to be burned. And said segments, whether arranged for coarse or fine fuel, may be merely shifted, and in doing this, I do not increase or diminish the total area of said openings which at all times equals approximately sixty per cent of the total area of the fire box.

A further object is to provide segments and a support for the same which co-operate to produce an automatic locking effect so that the said segments cannot come off when operated for the purpose of discharging the cinders and ashes therefrom, but may be easily removed when the grate is in a normal position and replaced by another segment when needed, without pulling the fire.

And still another object is to produce an automatic cleaning effect without waste of fuel by releasing and discharging the lower stratum composed of cinders and ashes with-

out violently disturbing the burning fuel thereon or, when desired, discharging all of the fuel into the ash pit. 55

And a still further object is when operating the grate to prevent a forward and backward movement of the fuel thereon by causing the front upper portion of each segment to block the backward or forward movement of the fuel while the adjacent segment produces a scraping effect to loosen and discharge the cinders and ashes through the opening between said segments produced by the peculiar shape and movement of the 65 said segment. And this movement and its effect are simultaneously duplicated by each of the segments composing the main portion of the grate. It will be further observed that the top portion of the segments conform to the arc of a circle but of a wider circle than could be operative in the space allotted in this grate and that the provision for adjusting the segments to the cross bar supports is nearer the back portion 70 of the segment than the front, and also, that the combined adjustment of the segments and the cross bars is such as to produce a rotary movement of the upper portion of the segments limited as required to 75 produce the desired effect. 80

And another and still further object is to produce a cross bar that is not only adapted to co-operate with the segments in automatically preventing their accidental displacement but to produce a stronger and more rigid structure with less weight of material and for this purpose I have adopted a construction similar to that of a railroad rail, the comparative strength and rigidity 85 of which is proven beyond question. Other features will be hereinafter described. 90

In the drawings accompanying and forming part hereof:

Figure 1 is a side elevation of my invention, the end walls of the furnace being shown in section. 95

Figure 2 is a section of the construction shown in Figure 1 but in a different position, and having certain parts omitted. 100

Figure 3 is a detail side elevation of two segments and associate parts showing them in an extreme position opposite to that of Figure 2.

Figure 4 is a detail showing the manner in which the shaking arms are connected to the operating bar.

Figure 5 is a side elevation, partly in section, of the operating lever and lock therefor.

Figure 6 is a longitudinal section, certain parts being omitted.

Figure 7 is a similar view with the grate sections rocked.

Fig. 8 is a horizontal section through a portion of a furnace, with parts broken away and showing the rows of segments arranged alternately with the openings staggered and with the openings in alignment.

Figure 9 is an enlarged side elevation of one of the grate segments in its normal position.

Figure 10 is a similar view showing the segment in one of its extreme positions.

Figure 11 is a top plan of two segments arranged with the openings staggered to burn finer fuel.

Figure 12 is a top plan of two segments arranged with their openings in alignment to provide larger spaces so that coarser fuel may be burned.

Figure 13 is an end view of the construction shown in Figure 11.

Figure 14 is a detail showing the bar rocked and the manner in which the segment is locked to its bar.

Figure 15 is a detail showing how the segments may be easily removed or replaced on the supporting bar.

Figure 16 is a perspective view of the front stationary grate and the manner in which it is placed on its support, this figure illustrating said front grate just before it is dropped into position.

Fig. 17 is a detail showing the manner in which the transverse support for the rear inclined grate is placed in position.

Figure 18 is a front elevation of several of the inclined rear grate bars.

Figure 19 is a perspective view of one of the inclined bars of Figure 18, detached.

Referring now to the details of the drawings by numerals: 1 designates the front wall of a furnace, 2 the bridge wall, 3 the side and 4 the dead plate thereof, these parts of course being illustrated in conventional form only since my invention does not reside therein and they may therefore be of any approved construction. The aforesaid dead plate 4 is provided with a transverse supporting flange 5. Upon this dead wall are supported the front ends of the longitudinal supporting bars 6, the rear ends of which are carried by the bridge wall 2. At their forward ends, these bars 6 are preferably recessed as shown at 10 and 12 to receive the end lugs 14 and 16 of the front stationary grate 18 as shown in Figures 8 and 16. And near their rear ends,

said longitudinal supporting bars are preferably formed with recesses 20 into which is dropped the transverse support 22 for the rear inclined grate bars 24 shown in Figures 18 and 19. At this point I desire to call attention to the lugs 26 on the transverse support 22 which are designed to fit into recesses 28 in the longitudinal supporting bars 6 and prevent the transverse support from being raised accidentally. This transverse support 22 is provided with a number of openings 30 as shown in Figures 8 and 18 to receive the downwardly projecting lugs 32 of the inclined grate bars 24. The form of these bars is novel and I desire to call attention specifically to them. As shown in Figures 18 and 19, each bar 24 is provided with side ribs 34 which are arranged to abut against the ribs of the adjacent bars as shown in Figure 18. In addition to acting as spacing means, these ribs 34 also act to divide the spaces between the bars 24 preferably into narrow channels 40 between the bars below the ribs 34 and into wider air spaces 42 between the bars above said ribs as clearly seen in Figure 18. These narrow spaces 40 permit the air from the ash pit to enter the fuel bed and prevent burning out the grate bars; while the wider air spaces 42 permit a larger volume of air to pass upwardly at the point where the fuel bed is at its minimum depth at the very point where the bars abut against the bridge wall. At this point the stratum of fuel is quite thin, and hence the larger volume of air passing through the large air spaces 42 greatly assists in the combustion of the gases just at the point where they pass over the bridge wall.

The longitudinal supporting bars 6 in addition to supporting the fixed front grate 18 and the rear inclined grate bars 24, also support the movable grates which will now be described. The movable grates, in the embodiment as illustrated in Figure 8, comprise six oscillating grates and two dumping grates 50. The latter may be of any desired form and as shown are formed with trunnions 52 journaled in the longitudinal supporting bars 6 and have downwardly projecting shaking legs 56 which are connected with a dumping lever 58 provided with a handle 60. The oscillating grates are novel and may be described as follows: In their preferable embodiment, they are formed in the shape of segments 70 and are supported on transverse bars 72 which may be of any desired shape but preferably of the shape of railroad rails as giving the greatest strength for the weight of metal. Each transverse bar 72 has trunnions 74 journaled in the longitudinal supporting bar 6 as illustrated in Figure 8. In order to oscillate the grate segments 70, each bar 72 has attached to it two shaking lugs 76 shown in Figures 3 and

4 between which is fitted a connecting bar 80 by which the grate segments may be oscillated. This bar 80 is connected with a pivoted lever 82 supported in a bracket on the front of the furnace (see Figure 5). The lever 82 may be fitted with an operating arm or handle 84^a, and at its rear side is provided with a recess 86 into which fits a pivoted pawl 88 which will lock the lever 82 in just the position to maintain the grate segments 70 in their normal position shown in Figures 1, 6, 8 and 9. When it is desired to shake the grates, the operator moves the lever or handle 84^a slightly and this releases the pivoted pawl 88 so that it will drop by gravity to the position shown in dotted lines in Figure 5. After the grates have been shaken the operator moves the handle 84^a to the proper position and then moves the pawl 88 so that it again enters its recess and locks the lever 82 as shown in full lines in Figure 5. The grate elements themselves are of very simple character as will be seen from an inspection of Figures 9 and 11. They are mere segments resting upon the transverse bars 72 and while they rest thereupon so that they can be easily slipped thereon and as easily removed, they are locked so that they cannot be accidentally shoved out of position by the operator using a scraper or otherwise. To this end each segment 70 is provided with a notch 72^a of preferably the shape shown in Figures 9, 10, 14 and 15. The walls constituting this notch are preferably formed with a curved upper part 84 substantially the same shape as the top of the bar 72, but at one side the wall is enlarged outwardly as shown at 87, and one of the side walls is provided with a bottom lug 89 designed to co-act with the base of the bar 72. Therefore when the device is located as in Figure 9, it is impossible to remove the segment from its bar 72 without first moving it on its center so that the bottom lug 89 is clear of the base of the bar. Likewise, when it is in the position shown in Figure 14, the segment cannot be removed by shoving in the direction of the arrow *a* but now it is not the lug 89 which locks it, but the fact that it binds at the point shown by arrow *b*. However when it is desired to remove a segment it is merely necessary to catch the segment to the left of its center as viewed in Figure 9 until it moves slightly on its center to the position shown in Figure 15 when it can be easily removed vertically from its bar. It will be obvious that it can be easily replaced by permitting it to slip downward over its bar 72.

I also call attention to the fact that the notches 72^a in the grate segments 70 are not in the center but are at one side of the center of the segments so that when it is desired to clear the grates, they can be moved to the extreme position shown in Figure 7 where the spaces between the segments will be wider than if the segments were moved to the same extent in the opposite direction. I also desire to call attention to the fact that the surface of the segments, when the segments are oscillated on their trunnions, scrape against the lower surface of the fuel bed, and this releases the ashes and cinders from the lower stratum of the fuel bed without agitating the whole fuel bed, and thereby preventing waste of unburned fuel.

In my preferred construction, I arrange the segments in two different ways as shown in Figures 11 and 12. Thus in Figure 11 there are two identical segments arranged so that the openings forming the corrugated edge of each segment are not in alignment, but are in a staggered relation. On the contrary, in Figure 12, the segments are alternated, that is, every alternate segment is reversed, so that the openings of one segment are directly opposite the openings of the adjacent segment. This makes it possible to arrange the segments to burn fine coal when they are arranged as in Figure 11, or to burn coarser coal when the segments are alternated as in Figure 12 to provide the larger openings. From an inspection of Figure 8, it will be seen that both arrangements are used. The first row of segments is arranged as in Figure 11 to provide the small openings; the second row of segments is arranged as in Figure 12 to provide the larger openings; the third row as in Figure 11, etc. It will be obvious that the segments can be shifted, one with respect to the other, so that if it is desired to burn fine coal, the segments of like kind are placed next to each other. If it is desired to burn coarser coal, the segments can be alternated. I deem this shiftable arrangement, especially when coupled with the locking feature, as important.

The non-rigid seating of the segments on their bars provides a backward independent movement of the fuel supporting segments relative to the adjacent segments which greatly assists in dislodging adhering clinkers that frequently spread out like a pancake formation over the grate surface, and the tarry substance runs down into and fills the spaces or openings in the grate to such an extent that it frequently requires the use of a hammer and coal chisel to remove the same from grates which have a rigid construction. With my improved non-rigid construction, adherence of clinkers is almost entirely prevented by the independent free movements of the segments backward and forward and also laterally with the slice bar, as room for such lateral movement is always provided in assembling the segments on the bar, which, it will be observed is impossible in any form of rigid construction. The beneficial results that are secured by this

non-rigid construction differentiates it from all known grates, and it constitutes a distinguishing and one of the valuable features of my present invention.

5 From the foregoing and the accompanying drawings, it will be seen that I have constructed a furnace grate of novel character, and one having the other characteristics hereinbefore set forth. It will be manifest that in case of breakage of any of the segments, the broken segments can be easily removed without drawing the fire and new ones as easily inserted; that said segments, though easily removable when they are 10 lifted in the proper manner, are yet locked on the supporting bars so that they cannot be displaced when using a scraper, etc.; that if it is desirable or necessary to change from a fine to a coarse fuel, or vice versa, 15 the segments can be re-arranged so that the openings may be small or large; that the leaning grate at the bridge wall is so constructed that it performs a double function, first, as an aid to better combustion of the 20 gases by passing the superheated air through relatively large openings in said leaning grate at the point where the fuel is quite thin, and by passing a relatively large volume of super heated air through the leaning 25 grate, to prevent the formation of clinkers at this point. In addition to the advantages above outlined, the time and labor actually required to operate and to clean are greatly 30 reduced, and a large percentage of fuel is saved. Thus, if time permits, the fuel on the rear dumping grates may be allowed to burn thoroughly, and then be dumped; or, if steam requirements will not permit such 35 action, the attendant may use a scraper and pull the good fuel off of the dumping grates, and dump what remains thereon, and then after setting the rear grates, all the unburned fuel may be pushed from the main 40 grates onto said rear grates, and the remaining cinders may be dumped through the 45 segmental grates, after which the incandescent fuel is brought forward from the rear grates and distributed over the main grates, when fresh fuel may be put on, and the task 50 completed.

It will be manifest that changes and modifications may be made without departing from the spirit of my invention, the scope of which is set forth by the appended claims.

55 What I claim as my invention is:

1. Furnace grates including supporting bars, oscillating transverse bars supported thereon and grate segments having open notches with rounded inner ends and diverging opposite edges, the outer end of one edge of each slot being provided with an in-turned bottom lug for engaging one of the transverse bars when said bar is against one side of the slot.

60 2. In a device of the character described,

the combination with supporting bars, of a transverse support for a grate, and having lugs on one side thereof, the supporting bars having recesses to receive the transverse support and having secondary recesses 70 within the first-mentioned recesses for receiving the lugs.

65 3. In a device of the character described, the combination of transverse bars having cylindrical upper portions, and grate segments having notches to fit over said cylindrical upper portions, the upper ends of said notches co-acting with said bars and having enlarged portions permitting the segments to be displaced for easy removal and having 80 parts of their walls co-acting with said bars to lock the segments from displacement when in one extreme position, said segments having ribs or flanges on their walls co-acting 85 with the supporting bars.

90 4. In a device of the character described, the combination with dumping grates, of supporting bars having recesses in the front ends thereof, a stationary grate having a plurality of lugs on each end thereof, said recesses being adapted to receive the lugs and support the stationary grate.

95 5. In a device of the character described, the combination with dumping grates, of inclined bars, a transverse support having openings therein, the inclined bars having lugs which fit into the openings in the transverse support, and having side ribs which abut each other when the bars are in place.

100 6. In a device of the character described, the combination with dumping grates, of inclined bars, a transverse support having openings therein, a bridge wall, the inclined bars having lugs which extend into the openings in the transverse support and provided with side ribs which abut each other when the bars are in place and form a division between spaces above and below the ribs for the passage of air, the uppermost spaces being of greater width than the lower spaces 105 to permit the flow of a greater volume of air through at the top.

110 7. In a device of the character described, the combination with front and bridge walls of a furnace, and a dead plate supported by the front wall, of supporting bars, transverse bars having trunnions journaled in said supporting bars, grate segments supported by the transverse bars, the segments having notches in one side thereof and having in-turned lugs in position to engage the transverse bars, means for shaking the grate segments, dumping grates having trunnions journaled in the supporting bars, means for dumping the dumping grates, a transverse support carried by the supporting bars, and inclined bars having lugs extending into openings in the transverse support.

115 8. The combination with a transverse supporting bar having a rounded edge, of a 120

- grate segment having a notch, the inner end of which is rounded upon the arcs of two circles, of which only one at a time is adapted to receive and approximately conform to the rounded edge of the bar, one being located nearer the outer end of the notch than the other and adapted to form clearance for the rounded edge of the bar when the grate segment is attached or detached therefrom.
- 10 9. The combination with a transverse supporting bar having a rounded edge, of a grate segment having a notch, the inner edge of which is rounded upon the arcs of two circles, of which only one at a time is adapted to receive and approximately con-
- form to the rounded edge of the bar, one arc being located nearer the outer end of the notch than the other and adapted to form clearance for the rounded edge of the bar when the grate segment is attached or detached therefrom, the walls of the notch being non-parallel and having a constricted outer end slightly wider than the widest part of the supporting bar. 20
- In testimony whereof I affix my signature 25
in presence of two witnesses.
- THOMAS E. MARTIN.
